UNITED STATES PATENT OFFICE.

ADOLPH FREDRICK STROMBERG, OF ATWATER, MINNESOTA.

DESIGN FOR A MEMORIAL-SERVICE FLAG.

52,357.

Specification for Design.

Patented Aug. 27, 1918.

Application filed May 9, 1918. Serial No. 233,600. Term of patent 3½ years.

To all whom it may concern:

Be it known that I, ADOLPH FREDRICK STROMBERG, a citizen of the United States, residing at Atwater, in the county of Kandiyohi and State of Minnesota, have invented a new, original, and ornamental Design for a Memorial-Service Flag, of which the following is a specification, reference being had to the drawing forming a part thereof.

The figure is a side elevation of a memorial service flag embodying my invention.

I claim:

The ornamental design for a memorial service flag, as shown.

ADOLPH FREDRICK STROMBERG.

In the presence of—

CHAS. A. SWENSON,
NELS BLOMBERG.
